UNITED STATES PATENT OFFICE.

JERROLD F. WALTON AND WILLIAM T. FAVORITE, OF STURGIS, MICHIGAN; SAID FAVORITE ASSIGNOR TO SAID WALTON.

ADJUSTABLE CHAIR.

1,037,565.

Specification of Letters Patent.

Patented Sept. 3, 1912.

Application filed February 26, 1912. Serial No. 679,915.

To all whom it may concern:

Be it known that we, JERROLD F. WALTON and WILLIAM T. FAVORITE, citizens of the United States, residing at the city of Sturgis, county of St. Joseph, State of Michigan, have invented certain new and useful Improvements in Adjustable Chairs, of which the following is a specification.

This invention relates to improvements in adjustable chairs.

The main objects of this invention are: First, to provide an improved adjustable chair which is very easily adjusted and to any desired position within its scope. Second, to provide in an adjustable chair an improved adjusting mechanism which is comparatively simple in structure as well as being economical and durable.

Further objects and objects relating to structural details will definitely appear from the detailed description to follow.

We accomplish the objects of our invention by the devices and means described in the following specification.

25 The structure described constitutes one effective embodiment of our invention.

Other embodiments would be readily devised by those skilled in the art.

The invention is clearly defined and 30 pointed out in the claims.

A structure constituting an effective and preferred embodiment of the features of our invention is clearly illustrated in the accompanying drawing, forming a part of this 35 specification, in which:

Figure I is a side elevation of a structure embodying the features of our invention, with portions broken away to better show structural details. Fig. II is an inverted 40 view of the structure appearing in Fig. I. Fig. III is a detail perspective of our improved adjusting mechanism, as here embodied. Fig. IV is an enlarged detail vertical section through the adjusting mechanism. Fig. V is an inverted perspective 45 view of the clutch member 15. Fig. VI is a detail perspective of the forward end of the link 12. Fig. VII is a detail view of a modified form of the connection between the link 12 and slide 16. Fig. VIII is a detail 50 view of a modified form of the attaching ear for the bars 26.

In the drawing, similar reference numerals refer to similar parts throughout the several views.

Referring to the drawing, the chair frame preferably consists of rear posts 1 and front posts 2 which are extended to form the front and rear legs of the chair.

The posts are connected to the front and rear frame pieces 3 and the side frame pieces 4. The front and rear frame pieces are connected by the horizontally-disposed piece 5 on which the adjusting mechanism is mounted. On the upper ends of the posts 60 are arms 6. The arms, in the structure illustrated, are connected to the side frame pieces 4 by panel-like pieces 7.

The back, in the structure illustrated, is formed of side bars 8 connected by suitable 70 cross pieces 9, as is well understood. The back is hinged at 10. Secured to the back, preferably by arranging through the cross pieces 9, is a rod-like arm 11, the lower end of which extends below the pivots 10. The 75 adjusting mechanism is connected to this arm by means of the link 12. This link is preferably formed of two pieces or bars arranged side by side, the bars being spread at their forward ends and turned laterally 80 to form the ears 13. The forward ends of the springs 14 are secured to the ears 13, the rear ends of the springs being secured to the frame so that they tend to throw the back forwardly by pulling rearwardly on 85 the link when it is released. This link is adjustably secured by means of the clutch member 15, which, in the structure illustrated, is plate-like in form and provided with V-shaped teeth 16 on one edge. On 90 the under side of the plate is a pivot ear 17 which is embraced by the forward end of the link. A coacting clutch member 18 is provided, having V-shaped teeth 19 corresponding to the teeth 16 of the clutch member 15. These clutch members are, in the structure illustrated, slidably supported by 95 a bracket, designated generally as 20, having a slide way 21 for the clutch member 15 and a slide way 22 for the coacting clutch member 18. This bracket is provided with ears 23 and 24 for attachment to the frame piece 5, and also with upturned ears 25 to which the inner ends of the bars 26 are secured. (See Fig. 3.) The bracket with its 100 ears as described, is preferably formed integrally of sheet metal. At the outer ends of the bars 26 are turned laterally arms 27 which are secured to one of the side pieces 4 of the frame. One of the bars being longer 105

110

than the other, the proper spacing of the outer ends of these bars is secured, while their inner ends are held in a spaced relation by the bracket to which they are secured, as described.

5 Mounted between the bars on the pivot 28 is a lever 29 having an inclined end 30 adapted to coact with the inclined end 31 of the clutch member 18 in forcing the clutch member to its engaging position. The lever is actuated by the spring 32, preferably a rod spring as shown, its outer end being secured to the lever at 33 while its inner end engages the cross piece 34 on the bars 26. This cross piece not only retains the spring under tension to actuate the lever, but also serves to limit the upward movement of the lever, its downward movement being limited by engagement with the bracket 20. (See Fig. 4.) The lever 29 is 10 preferably operated by means of the button 35 in the arm of the chair, the stem 36 of which rests upon the lever 29 so that when the button 35 is pressed downwardly the inner end of the lever is lifted out of engagement with the clutch member 18, thus freeing the clutch member 15 and consequently the back, permitting its adjustment. When the lever is released the clutch members are 15 actuated to retain the back in its adjusted position.

Our improved adjusting mechanism is very easily manipulated; that is, it is easily engaged and disengaged to permit the adjustment of the back, and the back may be 20 adjusted to substantially any position within its limits. The structure is also of advantage in that it is simple and economical and very strong and durable.

25 In the modified form of the connection between the link 12 and slide 16, as shown in Fig. VII, the connecting lug 17^a and ears 17^b turned outwardly for the connection of the tension springs 14.

40 In the modification shown in Fig. VIII, only one of the bars is turned off at right angles to form an arm 27', for the purpose of attachment. The other bar is provided with a projection 26^a to properly space the 30 bars.

We have illustrated and described our improvements in detail in the form in which we have embodied them in practice. We are, however, aware that they are capable 45 of very considerable variation in structural details without departing from our invention, and we desire to be understood as claiming them specifically in the form illustrated, as well as broadly, within the scope 60 of the appended claims.

Having thus described our invention, what we claim as new and desire to secure by Letters Patent is:

65 1. The combination with the frame and back, of a link connected to said back, said

link being formed of pieces arranged side by side with their forward ends separated and turned laterally; springs connected to the laterally-turned ends of said link pieces and to said frame; a plate-like clutch member having V-shaped teeth on one edge thereof and a pivot ear on its under side arranged between the link pieces and pivoted thereto; a coacting clutch member having V-shaped teeth thereon and an inclined surface at its outer end; a bracket having transversely-disposed ways in which said clutch members are slidably arranged, and bar and frame attaching ears, said bracket being formed integrally of sheet metal; a pair of spaced bars secured to said frame at their outer ends and to said bar attaching ears of said brackets at their inner ends; a lever having an inclined surface at its inner end adapted to engage the inclined surface of said clutch member, pivoted between said bars; a rod spring arranged between said bars, its outer end being secured to said lever; a cross piece on said bars under which the inner end of said spring is arranged, said cross piece and bracket being adapted to limit the movement of said lever; and a button on said frame having a stem adapted to engage the outer end of said lever.

2. The combination with the frame and back, of a link connected to said back; a plate-like clutch member having V-shaped teeth on one edge thereof and a pivot ear for said link on its under side; a coacting clutch member having V-shaped teeth thereon and an inclined surface at its outer end; a bracket having transversely-disposed ways in which said clutch members are slidably arranged, and bar and frame attaching ears, said bracket being formed integrally of sheet metal; a pair of spaced bars secured to said frame at their outer ends and to said bar attaching ears of said brackets at their inner ends; a lever having an inclined surface at its inner end adapted to engage the inclined surface of said clutch member, pivoted between said bars; a rod spring arranged between said bars, its outer ends being secured to said lever; a cross piece on said bars under which the inner end of said spring is arranged, said cross piece and bracket being adapted to limit the movement of said lever; and a button on said frame having a stem adapted to engage the outer end of said lever.

3. The combination with the frame and back, of a link connected to said back, said link being formed of pieces arranged side by side with their forward ends separated and turned laterally; springs connected to the laterally-turned ends of said link pieces and to said frame; a plate-like clutch member having V-shaped teeth on one edge thereof and a pivot ear on its under side arranged

between the link pieces and pivoted thereto; a coacting clutch member having V-shaped teeth thereon and an inclined surface at its outer end; a bracket having transversely-disposed ways in which said clutch members are slidably arranged, and bar and frame attaching ears, said bracket being formed integrally of sheet metal; a pair of spaced bars secured to said frame at their outer ends and to said bar attaching ears of said brackets at their inner ends; and a lever having an inclined surface at its inner end adapted to engage the inclined surface of said clutch member, pivoted between said bars.

4. The combination with the frame and back, of a link connected to said back; a plate-like clutch member having V-shaped teeth on one edge thereof and a pivot ear for said link on its under side; a coacting clutch member having V-shaped teeth thereon and an inclined surface at its outer end; a bracket having transversely-disposed ways in which said clutch members are slidably arranged, and bar and frame attaching ears; said bracket being formed integrally of sheet metal; a pair of spaced bars secured to said frame at their outer ends and to said bar attaching ears of said brackets at their inner ends; and a lever having an inclined surface at its inner end adapted to engage the inclined surface of said clutch member, pivoted between said bars.

5. The combination with the frame and

back, of a link connected to said back; a sliding clutch member provided with V-shaped teeth connected to said link; a coacting clutch member provided at its inner end with engaging teeth and having an inclined surface at its outer end; means for slidably supporting said clutch members; a pivoted lever having an inclined surface at its inner end adapted to engage the inclined surface of said clutch member; a spring for actuating said lever; and a finger piece for operating said lever to release said clutch.

6. In an adjustable chair the combination of the chair frame; an adjustable back pivoted on said frame; a slideable clutch member in suitable ways on said frame; a connection from said slideable member to said back; a coacting clutch member to engage said slideable member and provided with an inclined surface; a lever having an inclined surface to coöperate with the inclined surface on said clutch member; a spring urging said lever against said clutch member; and means for manually manipulating said lever to release said clutch.

In witness whereof we have hereunto set our hands and seals in the presence of two witnesses.
